New York, N. Y., a corporation of Delaware

Original application May 3, 1935, Serial No.
19,563, now Patent No. 2,357,984, dated Septem-
ber 12, 1944. Divided and this application
March 27, 1944, Serial No. 528,317

1 Claim. (Cl. 250—36)

1

The present invention relates to frequency control systems, and more particularly to improvements in automatic frequency control networks. This application is a division of application Serial No. 19,563 filed May 3, 1935, patented September 12, 1944, as U. S. Patent No. 2,357,984.

There has been disclosed in U. S. Patent No. 2,294,100, patented August 25, 1942, various circuits for automatically varying the tuning of a resonant circuit independently of the normal tuning device. In these previous systems the results sought to be accomplished have in general been attained. However, additional investigation and experimentation has resulted in the development of further improvements in automatic frequency control systems.

The automatic frequency control systems to be explained in detail in a later portion of this specification involve in general two distinct units employed in a superheterodyne receiver. One of these units is a frequency discriminator, or frequency sensitive detector, that generates a bias varying with changes of the intermediate frequency signal carrier. The other unit is a control that is acted upon by the aforementioned bias, and whose function it is to vary the local oscillator frequency in a desired sense. The two units are so coordinated that if the intermediate frequency carrier tends to shift from its mid-band frequency value, the oscillator frequency changes sufficiently to restore proper alignment.

The automatic frequency control systems which comprise the subject matter of the present application are not only useful in facilitating the manual tuning operation of a superheterodyne receiver, but are also highly useful in maintaining the local oscillator frequency at a desired carrier setting for a long period of time, and throughout operation of the receiver during this period.

In addition to its aid and benefit in connection with the manual tuning of superheterodyne receivers, the presently disclosed frequency control systems can be used with benefit in connection with the automatic tuning of radio receivers of the superheterodyne type. In such instances the frequency control network functions as a vernier device to accurately tune the oscillator circuit after the automatic tuning mechanism has substantially adjusted the tuning device to its desired station position.

Accordingly, it may be stated that it is one of the primary objects of the present invention to provide improved automatic frequency control networks which are not only capable of usage in such a manner as to secure the aforementioned

results, but are also constructed so as to function in a positive and reliable manner.

Another important object of the present invention is to provide automatic frequency control networks based on an operating principle which is substantially different from that utilized in connection with the circuits disclosed in the aforementioned patent. The present operation is based upon the fact that when the plate 10 of the frequency control tube is coupled into the high potential side of the resonant circuit to be adjusted in tuning, and the grid of the control tube is excited by a voltage 90° out of phase with that appearing across the resonant circuit, then 15 the plate current in the control tube is similarly out of phase with the resonant circuit voltage, and the control tube presents a reactive effect across the resonant circuit; the magnitude of this reactive effect varies according to the frequency control bias impressed upon the control grid of the control tube by the frequency discriminator network.

Another object of the present invention is to provide an automatic frequency control system 20 for a superheterodyne receiver, the system comprising a frequency discriminator network functioning to provide a direct current bias which varies in magnitude with the shifting frequency of the intermediate frequency carrier; a reactance control tube being used in operative association with the local oscillator tank circuit in such 25 a manner that the plate current of the control tube is out of phase with the tank circuit voltage whereby the control tube simulates a predetermined reactance across the tank circuit, the magnitude 30 of the control tube reactance varying according to the discriminator bias which is impressed upon the control grid of the control tube.

Another object of the present invention may 35 be said to reside in the provision of a tunable oscillation circuit which is capable of being automatically tuned to different frequencies in a predetermined frequency range, there being an automatic frequency control system operatively associated 40 with the oscillation circuit in such a manner that the oscillation circuit is accurately and automatically tuned to resonance with a desired signal carrier when the tuning means of the oscillation circuit is adjusted to a predetermined 45 frequency, there being provided additional means for rendering the frequency control operative as soon as the oscillation circuit has been tuned to approximate resonance with said predetermined frequency.

55 Still other objects of the invention are to im-

2

prove generally the simplicity and efficiency of automatic frequency control systems for radio receivers, and more especially to provide such systems in an economical and practical manner; the control systems of the present invention being particularly characterized by their reliability and accuracy in operation.

Still other features will best be understood by reference to the following description taken in connection with the drawings in which I have indicated diagrammatically several circuit organizations whereby the invention may be carried into effect.

In the drawings:

Fig. 1 diagrammatically shows a superheterodyne receiving system embodying one form of the present invention.

Fig. 2 shows a modification of the frequency control network in Fig. 1;

Fig. 3 shows a further modification of the frequency control network in Fig. 1;

Figs. 4, 5 and 6 show additional modifications of the frequency control network of Fig. 1.

Referring now to the accompanying drawings, wherein like reference characters in the different figures designate similar circuit elements, the receiving system shown in Fig. 1 is of the superheterodyne type, and is shown as embodying an automatic frequency control network whose general organization is similar to that disclosed and claimed in the aforesaid Patent 2,294,100.

The receiving system embodies generally a grounded antenna circuit A which feeds a radio frequency amplifier 1 having a tunable input which is resonated to the desired signal frequency. The output energy of the amplifier 1 is impressed upon the tunable input circuit 3 of the first detector tube 2, the latter being shown by way of illustration as of the 6A7 type. The plate circuit of the tube 2 includes a tuned circuit 4 which is resonated to the operating intermediate frequency of the system, and the latter may be chosen to have a value, for example, of the order of 460 kilocycles (kc.). The intermediate frequency energy produced in the circuit 4 may then be amplified in one or more stages of intermediate frequency amplification, and by way of example two such cascaded amplifier stages 5 and 6 are shown. The numeral 7 denotes the tuned input circuit of the amplifier 5, whereas the numeral 8 denotes the tuned output circuit of the amplifier.

The intermediate frequency amplifier 6 is provided with a tuned input circuit 9 and a tuned output circuit 10, it being pointed out that the circuits 4, 7, 8, 9 and 10, as well as the input circuit 11 to the second detector, are each resonated to the operating intermediate frequency of the system. The second detector or demodulator of the system may be of any well known type, and may follow the construction, for example, shown in the aforesaid U. S. Patent 2,294,100. The local oscillator network comprises a tube 12 which is provided with a tunable oscillator tank circuit. The tank circuit includes the tuning condenser 13, and the series-arranged coil 14 and resistance R are connected in shunt with the condenser 13. The high potential side of the tank circuit is connected to the control grid of tube 12 through a blocking condenser 15, the usual grid return resistor 16 being connected to ground from the grid side of condenser 15.

The cathode of oscillator tube 12 is grounded, and the plate thereof is regeneratively coupled to the tank circuit by means of a coil 14' which

is magnetically coupled to coil 14. The positive potential required for the plate of oscillator tube 12 is fed to the plate through the feedback coil 14', and the low alternating potential side of the tank circuit is connected to a source of positive potential. This latter positive potential is provided for the plate of the frequency control tube to be described in further detail at a later point. The locally produced oscillations are impressed upon the grid 17, which is the nearest to the cathode of tube 2. The grid 17 is connected to the high alternating potential side of the oscillator tank circuit through a blocking condenser 18, the grid side of condenser 18 being connected to the cathode side of the grid bias network 20 by a resistor 19.

It will be observed that a dotted line denotes the mechanical uni-control device usually employed for operating the rotors of the variable tuning condensers of the signal and local oscillator circuits. It is to be clearly understood that the dotted line signifies the mechanical coupling between the rotors of condensers 13 and 3', and also with the rotors of the variable condenser usually employed in the input of amplifier 1. The frequency changing function in tube 2 is accomplished by means of electronic coupling, and this action is so well known to those skilled in the art at the present time that a mere reference thereto is believed sufficient.

The signal carrier amplitude at the demodulator input circuit 11 is maintained substantially constant over a wide range of carrier amplitude variation at the signal collector A by means of an automatic volume control arrangement, the latter being denoted as "AVC" in Fig. 1. The varying negative bias for securing the automatic amplification regulation is derived from the diode network operatively associated with the driver tube 21. The latter tube may be of the 78 or 6D6 type, and has its control grid coupled, for the impression thereon of intermediate frequency voltage to the high alternating potential side of the tuned output circuit 8 of amplifier 5. The signal path connected to the control grid of tube 21 includes a direct current blocking condenser 22, the control grid being connected to ground through a grid return resistor 23.

The plate of tube 21 is connected to a source of positive potential through two paths; one of these paths includes the coil P₁, while the other path includes the coil P₂. Each of coils P₁ and P₂ is shunted by a condenser 24. The AVC diode network comprises the auxiliary anode 25 which is disposed adjacent a portion of the cathode of tube 21 outside the main electron stream to the plate of the tube. The grounded cathode lead of tube 21 includes the control grid bias network 26; the resistor 23 acting as a conducting path for the grid bias of the control grid of the driver tube. Intermediate frequency energy is impressed upon the diode anode 25 through the direct current blocking condenser 27 which is connected between the plate of tube 21 and the diode anode 25. The diode anode 25 has connected in circuit therewith a load resistor 28, the latter developing a direct current voltage across it when the intermediate frequency carrier amplitude attains a magnitude above a predetermined intensity level.

The anode side of resistor 28 is connected to the gain control electrodes of the controlled signal transmission tubes. In the present case the signal grids may act as the gain control electrodes, and the AVC lead is to be understood as being connected to the various grid circuits of

the controlled transmission tubes. The AVC lead is connected to the anode side of resistor 28 through a resistor 29 which acts to suppress pulsating components of rectified intermediate frequency voltage; the condenser 30 connected to ground cooperating with resistor 29 to provide a suitable time constant network for the AVC arrangement.

Those skilled in the art will recognize that the system described to this point is in general of a well-known type. Assuming that the signal range is in the present broadcast band and covers a range of frequencies from 550 to 1500 kc., and the oscillatory frequency is greater than the signal frequency, then the local oscillator frequency range will be from 1010 kc. to 1960 kc. if the intermediate frequency is to be 460 kc. As the intermediate frequency carrier amplitude at circuit 8 increases, the negative bias applied to the control grids of the regulated tubes by the AVC network increases, thereby reducing the amplification of each tube, and in this way the signal amplitude at the demodulator input circuit 11 is maintained substantially uniform regardless of the signal amplitude variation at collector A.

The frequency discriminator network comprises the double diode tube 31, and the latter may be, by way of specific illustration, of the 85 type with the triode section thereof unused. The anodes of tube 31, these anodes being designated by numerals 32 and 33, are connected to opposite sides of a resistor which develops the automatic frequency control (AFC) bias. This resistor has the cathode of tube 31 connected to the mid-point thereof, and therefore a single resistor may be employed or a pair of resistors of equal magnitude may be used instead. In any event the numeral 34 designates the resistor section between the cathode of tube 31 and the anode 32.

The resistor section 34' designates the load between the cathode of tube 31 and the diode anode 33. Each of the resistor sections 34 and 34' is shunted by a bypass condenser, and the anode side of resistor 34' is grounded. The secondary coil S₁, which is magnetically coupled to primary P₁, is connected between anode 32 and resistor section 34. The secondary coil S₂ is magnetically coupled to primary P₂, and the secondary is connected between the anode 33 and the grounded side of resistor section 34'. A condenser 35 is connected in shunt with coil S₁ and tunes the latter to a frequency on one side of the operating intermediate frequency, whereas condenser 36 is in shunt with coil S₂ and tunes the latter to a frequency located on the other side of the operating intermediate frequency.

The frequency control tube is shown by way of illustration as being of the pentode type, and its plate is connected by lead 37 to the high alternating potential side of the oscillator tank circuit. The cathode of control tube 38 is grounded through a grid bias network 39, and the control grid of tube 38 is connected to the anode side of resistor 34 through a path which includes the grid return resistor 40 and a lead 41. The lead 41 is designated by the letters "AFC" and is to be understood as denoting the automatic frequency control bias path. The lead 41 is adapted to be connected to ground by a switch 42, and it will be understood that the automatic frequency control bias path for tube 38 is operative only when switch 42 is open. When the switch 42 is closed, then the AFC path is short circuited to ground and is inoperative. The control grid of tube 38 is also connected to the upper end

of resistor R in the tank circuit of the local oscillator through a direct current blocking condenser 43, a bypass condenser 44 being connected between the low alternating potential side of the tank circuit and ground.

In considering the operation of the AFC system of the receiver shown in Fig. 1 it is first pointed out that a high degree of selectivity in a superheterodyne receiver is of no great use unless it is possible to tune the receiver with a corresponding degree of accuracy, and thereafter to maintain this accuracy. As is well known, if the tuning of a superheterodyne receiver is inadequate the high selectivity may actually become a detriment. For example, in all-wave, or multiband, receiver sets selectivity has been effectively increased 15 to 20 times over that usual for broadcast reception, merely because the received signal frequencies have been increased by that amount without changing the intermediate frequency band width, i. e., at 20 megacycles (mc.) the nominal 10 kc. intermediate frequency band is only 0.05% of the base frequency. To meet this increase in selectivity in present-day receivers manual tuning means have been improved by the employment of more smoothly working speed-reducing mechanical movements to operate the variable tuning condenser.

Nevertheless the maintenance of proper tuning after the station signal has once been correctly brought in, is a problem that requires a reliable and accurate solution. Local oscillator drift, if not corrected by more or less frequent manual readjustment, is capable of mistuning the signal by many channels in the course of a few hours' run. In the broadcast band, conditions are quite as serious if quality of reproduction is a consideration. The average broadcast set user does not tune the receiver well enough to obtain the best quality it is capable of giving; this is due not only to negligence, but to a great extent because of the lack of necessary skill, and in the latter case the mechanical design of the set is a contributing factor. These considerations show the need for supplementing the accuracy of manual or automatic tuning by an automatic frequency control device.

It will therefore be seen that it is the essential object of the frequency discriminator and frequency control tube to cooperate to adjust the oscillator frequency so as to make it appear as if the signal carrier frequency has been adjusted precisely to the center of the receiver I. F. intermediate frequency band and to anchor it there in spite of small original maladjustments of tuning, or other causes that subsequently arise from thermal changes and the like. It will now be seen that the frequency discriminator network generates a bias, applied through lead 41, which varies with changes of the predetermined I. F. value; the control tube 38 has its gain varied by the AFC bias, and the control tube functions to vary the local oscillator tank circuit in frequency. The discriminator and control units are so inter-related that if the I. F. carrier frequency tends to move away from the operating I. F. mid-band position, then the oscillator frequency changes sufficiently to restore the proper alignment. Such units, and their construction for performing these functions are generally disclosed in aforementioned U. S. Patent 2,294,100.

The two similar I. F. transformers, between tube 21 and tube 31, have their primaries P₁ and P₂ connected in parallel in the plate circuit of the driver tube 21. This composite primary is

tuned to the mid-band frequency of the I. F. band; in other words the composite primary is tuned to 460 kc. The secondaries S_1 and S_2 are loosely coupled to their respective primaries and are tuned to different frequencies lying above band and below the mid-band frequency by equal amounts. Thus, the secondary S_1 may be tuned to 462 kc., and the secondary S_2 may be tuned to 458 kc. The AFC diode is driven from the composite primary associated with the driver tube 21, and the diode load 28 not only functions as such, but also acts to damp the composite primary in order to aid in de-coupling the secondaries from each other and so causes them to act like isolated single tuned circuits.

The secondaries S_1 and S_2 are each connected into one of the plates of the double diode tube 31, and the cathode of this tube is "floating" for direct current voltage. One of the diodes returns to ground, and the AFC bias output is taken from the other diode return. The output of the discriminator is the algebraic difference between the rectified outputs of the two diodes. If the I. F. carrier frequency is off center frequency, or the operating I. F. value, towards the resonance of coil S_1 , then the diode including anode 32 will produce the greater rectified voltage output of the two diodes, and the generated AFC bias will be negative with respect to ground. Conversely, if the I. F. carrier frequency is off in the other direction the reverse will be true. That is to say, the AFC bias will be positive in polarity. When the carrier frequency is exactly aligned with the operating frequency of 460 kc., the bias on the grid of tube 38 will equal the initial bias value thereof since the AFC bias will then be zero.

It will be noted that the AFC diode is driven from the driver tube which feeds the discriminator network. This mode of generating AFC bias is employed, in preference to deriving AFC input energy from the circuit 11, because there is thus obtained a higher carrier input into the AFC rectifier. A considerable voltage delay may be used on the AFC diode. Another advantage of taking off the AFC bias in this manner is that the signal modulation at the second detector is not distorted by the demodulation produced by the AFC diode.

If the AFC driver tube also drives the AFC rectifier its output is automatically held nearly constant no matter where it is connected. Therefore, the grid of the driver tube may be connected at the primary or secondary of the transformer preceding the last I. F. amplifier tube. This has the merit of giving a broader channel for the AFC and the AVC than for the audio detector. The gain of the last I. F. stage should be considerably decreased to avoid second detector overload.

As clearly explained in aforementioned U. S. Patent 2,294,100, maximum AFC sensitivity is obtained when the discriminator characteristic has the greatest slope. This occurs when the two secondaries S_1 and S_2 are so tuned that points of maximum slope on their individual resonance curves are made to coincide. The control circuit acts to vary the oscillator frequency and this variation may be thought of as if due to a variation in capacity, or of an inductance. The total tank circuit reactance may be considered to consist of two parts viz., that part physically present as in the variable tuning condenser or the tuning coil, and that part reflected by the control tube circuit. The latter is a func-

tion of the I. F. carrier frequency, and its magnitude varies with the carrier frequency shift from I. F. mid-band frequency.

In aforementioned U. S. Patent 2,294,100 the control tube has been shown as reflecting capacity into the tank circuit, or the plate resistance of the control tube has been connected in series with a reactive element in the tank circuit. Additional investigation and experimentation have revealed frequency control circuits which make use of a different principle. It will be noted that the plate of control tube 38 is coupled into the high potential side of the tank circuit, and that the grid of the control tube is excited by an alternating voltage which is 90° out of phase with that appearing across the tank circuit. The plate current in the control tube is then likewise out of phase with the tank voltage, and accordingly the plate to cathode impedance of control tube 38 looks like a reactance to the tank circuit.

The sign of the reactance presented to the tank circuit by the control tube depends upon the nature of the impedance across which is developed alternating voltage to be fed to the input electrodes of the control tube. The magnitude of the reflected reactance depends upon the value of the AFC bias impressed upon the control grid of control tube 38, as this varies the mutual conductance, and proportionately the magnitude of the plate current, of the control tube. In Fig. 1 there is shown one method of obtaining the out-of-phase excitation for the grid of the control tube, and it will be noted that this is accomplished by taking the alternating voltage across resistance R . The effect of this arrangement is to produce an inductive effect across the tank coil 14. In other words, the plate to cathode impedance of tube 38 simulates an inductive reactance across coil 14. As the plate current of tube 38 is decreased the shunting effect of the reflected or simulated inductance is decreased, and the effective inductance of the tank circuit will therefore increase. This results in a decrease of oscillator frequency.

A specific example will be given to illustrate the operation of the control tube 38. Assume that the set is to be tuned to a signal of 600 kc.; the local oscillator frequency if higher will have to be 1060 kc. to produce an I. F. of 460 kc. As the tuner device is adjusted from 500 to 600 kc., the oscillator condenser 13 tunes the tank circuit from 960 to 1060 kc. When the tank circuit is within 2 kc., for example, of 1060 kc. (1058 kc.), the I. F. value is 458 kc. Since this is the frequency of the circuit S_2 , rectified voltage will be developed across resistor 34'. The control grid of tube 38 will, therefore, become less negative than its initial negative bias value with respect to ground due to its connection through lead 41 and resistor 34' to the cathode side of resistor 34'. The plate current flow of tube 38 increases; this will result in an increase in the inductive reactance reflexed across coil 14. Thus, the effective inductance in the tank circuit decreases; the oscillator frequency, therefore, increases.

The increase in frequency of the tank circuit will be such as to bring the local oscillation frequency to 1060 kc. Then the proper I. F. value of 460 kc. is secured, and the set sounds "tuned-in" to the listener. The reverse action takes place, of course, when the set is tuned away from the desired setting of 600 kc. Within 2 kc. on either side of 600 kc. the AFC system will act to "anchor" the tuning of the receiver. When the receiver is tuned beyond the permissible limits of a carrier

setting, the AFC action is suspended until the limit of the adjacent channel is reached. In this way the normally highly selective superheterodyne receiver is rendered easily tunable; a range of some 4 kc., for example, is provided within which the set may be tuned and yet distortionless reproduction be secured. The same operation is secured when the local oscillator circuit constants vary due to thermal, or other, effects. The AFC acts to bring the oscillator frequency back to the desired operating value so as to produce the operating I. F.

There are numerous methods of obtaining the out-of-phase grid voltage for the control tube 38. In order to make it clear to those skilled in the art how such different modes of procedure may be achieved, the following analysis of the operation of tube 38 and its circuits is furnished. It is to be clearly understood, however, that the analysis is theoretical in nature, and in no way affects the demonstrated operation of the reactance control network.

It can be shown, in general, for an oscillator network of the type illustrated in Fig. 1 (that is, the tank circuit and the tube 38 with its circuits) that the combination of the control tube 38 and the oscillator presents to the tank circuit an effective impedance which is the negative reciprocal of the control tube impedance with respect to the resistance product of both oscillator and control tubes. For example, a capacity is the reciprocal of an inductance with respect to a resistance product; the reciprocal of a shunt combination is a series combination.

A practical resistance value for resistor R in Fig. 1, for a broadcast local oscillator, is about 100 ohms. With the G_m mutual conductance of tube 38 equal to 1000 micromhos, the frequency change is about 5 percent. This permits a variation of plus or minus 25 kc. at 1 mc., which seems ample for the purpose. The tuned impedance of the tank circuit is unaffected by the control action. Constant oscillator amplitude with frequency change is one of the advantages of the present arrangement.

The series resistor R is not confined to the inductive leg of the tank circuit. For example, and as shown in Fig. 2, the resistor R_1 is placed in the capacitive leg of circuit 13-14. In this case the control tube cathode to plate impedance will appear as a resistance-capacity arm across the tank circuit; increase in the G_m of the control tube will now lower the oscillator frequency. It is necessary, in this case, to reverse the AFC connection to the discriminator network. Lead 41 is, therefore, connected to the anode side of resistor 34' and the anode side of resistor 34 is grounded.

Another method of securing the out-of-phase grid voltage for tube 38 is shown in Fig. 3. Here the reactive element is condenser C which is connected in series with the oscillator tickler coil 14'. Condenser C is grounded, and choke 59 is used to feed the direct current voltage to the plate of oscillator tube 12. The current flowing in the external plate circuit of tube 12 is in phase with the tank circuit voltage. A reactive element in the plate circuit will, therefore, develop an out-of-phase voltage which is impressed upon the control grid of tube 38. The cathode to plate impedance of tube 38 presents a negative inductance across the tank circuit; the net result is an increase in effective inductance in the oscillator tank circuit. The AFC connection must,

then, be reversed in polarity with respect to that shown in Fig. 1.

If the capacitive reactance C is replaced by an inductance coil then a negative capacity will be reflected across the tank circuit. If a negative inductance, say the mutual inductance of a transformer, were used in place of C, it would be reflected as a positive capacity. Any resistive element reflects as a negative resistance, or conductance, and tends to aid the feedback of the oscillator.

In Fig. 4 is shown a modification of the method of securing out-of-phase voltage; it differs from that of Fig. 3 in that the out-of-phase voltage is taken from across the tickler coil 14'. The plate to cathode impedance of the control tube, in this case, presents a negative capacity across the tank circuit. It is not necessary to change the AFC connection to the discriminator network from that shown in Fig. 1.

It may be that the reflected reactance from the tank circuit will give rise to an in-phase component across coil 14'. This may be eliminated by using the arrangements shown in Figs. 5 and 6. In Fig. 5 the coil L_1 is coupled to tickler 14', but it is not coupled to tank coil 14. The out-of-phase voltage across coil L_1 is impressed upon the control grid of tube 38 through coil L_2 ; the latter coil is coupled to coil L_1 . The plate to cathode impedance at control tube 38 presents a negative capacity across the tank circuit 13, 14; the AFC connection 41 is the same as that in Fig. 4. In Fig. 6 there is shown the effect of reversing the end connections of coil L_2 . The plate to cathode impedance of tube 38 now presents a positive capacity across the tank circuit. The AFC connection 41 must be reversed in polarity as shown. It is, further, pointed out that the circuit of Fig. 3, wherein the out-of-phase voltage is derived from across the condenser C, can be used to avoid the in-phase component of Fig. 4.

While there have been indicated and described several systems for carrying this invention into effect, it will be apparent to one skilled in the art that this invention is by no means limited to the particular organizations shown and described, but that many modifications may be made without departing from the scope of this invention.

50 What is claimed is:

In combination, a tuned tank circuit including a coil and a condenser connected in parallel, an electron discharge device regeneratively connected to the tank circuit whereby oscillations are set up at a frequency determined by the tuning of said tank circuit, a reactance tube having an anode, a cathode, and a grid, the anode and cathode being connected to the tuned circuit so as to vary the effective tuning of the tank circuit in accordance with electron current flow from the cathode to the anode of said reactance tube, a coil connected between the grid and cathode of said reactance tube, a pair of serially connected coils for subjecting the grid and cathode of said reactance tube to oscillatory voltages in quadrature with the oscillatory voltages across said tank circuit, one of said serially connected coils being inductively coupled to the coil of said tank circuit and the other of said serially connected coils being inductively coupled to the coil connected between the grid and cathode of said reactance tube, and said regenerative connection comprising said serially connected coils, and a circuit connected to electrodes of said reactance tube for varying the

11

electron flow from the cathode to the anode thereof, and thereby the frequency of oscillations set up by said device and tank circuit, in accordance with the control potentials.
